UNITED STATES PATENT OFFICE.

HARRY L. OWEN, OF OKMULGEE, OKLAHOMA.

VARIABLE COUNTERWEIGHT FOR PUMPING APPARATUS.

Application filed December 4, 1925. Serial No. 73,192.

This invention relates to counterweights of the kind that are used with pumping jacks and with pumping rigs of the type that comprise a walking beam.

The object of my invention is to provide a variable counterweight that is inexpensive to manufacture, that is easy to install, remove or adjust, and which is of such construction that the elements of which it is composed are interlocked with each other in such a way that it is impossible for them to become accidentally disassembled.

Figure 1 of the drawings is a side elevational view of a portion of a well pumping rig equipped with a counterweight constructed in accordance with my invention.

Figure 2 is an enlarged top plan view of said counterweight, with the guide rods and hanger rod shown in section, said view being taken on the line 2—2 of Figure 1.

Figure 3 is a vertical transverse sectional view of said counterweight, taken on the line 3—3 of Figure 2, with the hanger rod shown in elevation; and

Figure 4 is a vertical longitudinal sectional view of said counterweight, taken on the line 4—4 of Figure 2, with the guide rods and hanger rod shown in elevation.

I have herein illustrated my invention embodied in a counterweight for the walking beam of a well pumping rig, but I wish it to be understood that my invention is applicable to counterweights for individual pumping units, such as pumping jacks. In the drawings A designates the walking beam of a pumping rig, B designates a pair of stationary, vertically-disposed guide rods, C designates my variable counterweight which slides on said guide rods, and D designates the hanger rod that is used to connect said counterweight to one end of the walking beam A. The counterweight C is made up of a number of elements 1 arranged preferably in superimposed relation and provided with co-operating means that effectively prevent said elements from becoming accidentally disassembled or from moving out of operative relationship with the guide rods B and hanger rod D. In the preferred form of my invention herein illustrated the elements 1 consist of substantially oblong-shaped castings arranged one above the other on a supporting plate 2 that is sustained by the hanger rod D, and each provided with three open-ended slots α extending inwardly from one of the longitudinal

side edges of same, as shown in Figure 2, which are adapted to receive the guide rods B and the hanger rod D. The elements 1 are intended to be arranged in reverse position, namely, with the slots α in one element extending in the opposite direction to the slots α in the adjacent element or elements, and said elements are provided with co-operating means that effectively prevent said elements from moving laterally relatively to each other. The means just referred to can be constructed in various ways without departing from the spirit of my invention, but one means that I have found to be very effective consists of co-operating projections and recesses on the meeting faces of the elements 1 disposed so that they interlock said elements with each other and cause said elements to remain in vertical alignment, even when the counterweight is subjected to abrupt shocks and jars. In the form of my invention herein illustrated each of the elements 1 is provided on its top side with a projection 3 constructed in the form of a rib whose outline conforms to the outline of said element, and is provided on its underside with a recess or groove 3^a of corresponding form or outline that is adapted to receive the rib 3 of the next lowermost element.

Due to the fact that my improved counterweight is made up of a number of separate elements, it can be varied to increase or decrease the weight of same simply by adding more elements 1 or by removing some of said elements. The operation of varying or adjusting the counterweight can be effected quickly because no screw-threaded fastening devices are used to retain the elements 1 in operative position, and notwithstanding the fact that said elements can be assembled and disassembled quickly, they cannot drop off the hanger rod or move out of operative relationship with the guide rods B, even when the counterweight is subjected to a severe shock or jolt, due to the fact that they are interlocked with each other by co-operating ribs and grooves on their meeting faces. In addition to the desirable features above pointed out, a counterweight of the construction above described is inexpensive to manufacture, as it is composed of a number of duplicate castings of simple design.

Having thus described my invention, what I claim as new and desire to secure by Letters Patent is:

A counterweight composed of a verti-

cally-reciprocating hanger rod, a horizontally-disposed supporting plate sustained by said rod, a pair of vertical, stationary guide rods on which the counterweight travels, arranged parallel to and in alignment with said hanger rod, a number of substantially oblong-shaped weight elements arranged horizontally in superimposed relation on said supporting plate and each provided with three open-ended slots that receive said

hanger rod and guide rods and which are disposed transversely of the element, said elements being arranged so that the slots in adjacent elements are oppositely-disposed, and ribs and grooves on the top and bottom faces of said elements of approximately oblong shape in outline, that interlock said elements with each other. 15

HARRY L. OWEN.
